CLAIM

The ornamental design for a drinking vessel, as shown and described.

DESCRIPTION

FIG. 1 is a top perspective view of a first embodiment of a drinking vessel, according to the invention;

FIG. 2 is a bottom perspective view thereof;

FIG. 3 is a front side view thereof, the rear side view, the right side view and the left side view all being identical to the front side view;

FIG. 4 is a top view thereof;

FIG. 5 is an additional top view thereof with all broken lines removed to clearly illustrate the claimed design; and

FIG. 6 is a bottom view thereof.

FIG. 7 is a top perspective view of a second embodiment of a drinking vessel, according to the invention;

FIG. 8 is a bottom perspective view thereof;

FIG. 9 is a front side view thereof, the rear side view, the right side view and the left side view all being identical to the front side view;

FIG. 10 is a top view thereof;

FIG. 11 is an additional top view thereof with all broken lines removed to clearly illustrate the claimed design; and,

FIG. 12 is a bottom view thereof.

The broken lines shown in the figures are for illustrative purposes only and form no part of the claimed design.
